HARRY A. DOUGLAS, OF BRONSON, MICHIGAN

ELECTRIC LAMP

Application filed October 23, 1929. Serial No. 401,720.

My invention relates to lamps which employ lamp receiving sockets and holders for the sockets. The invention is of particular importance where such a lamp is equipped 3 with a concave reflector which carries the holder whose bore is in register with an opening provided through the reflector. The invention has for its general object the provision of means whereby the lamp may be fixed 10 with respect to said holder and, where the lamp is equipped with a reflector, may be fixed with respect to the latter element, also. The invention finds particular use in connection with lamps having parabolic reflectors and 15 enables the fixed relationship of the lamp filament with respect to the parabolic axis on which the filament is preferably located. A lamp thus constructed will direct light in 20 a fixed path with respect to the axis of the reflector, thereby avoiding difficulty now frequently encountered in the adaptation of reflecting lamps to automotive vehicles, bodily or other adjustment of the lamps having frequently been required when the users happen 25 to find that the light is improperly directed.

In my copending application Serial No. 403,613 filed October 30, 1929 (case 256), I have broadly claimed a lamp receiving socket within a holder and smaller in cross section 30 than the holder, and means pressing the socket laterally against one side of the holder. The structure disclosed in the aforesaid copending application employs a concave reflector with respect to which the socket holder 35 is fixed, the bore of the socket holder being in register with an opening that is formed through the reflector to permit of the insertion of the base of an incandescent lamp. The structure of the aforesaid application is 40 also inclusive of spaced apart spacing means intervening between the holder and socket in the place at which the socket is pressed against the holder.

The structure disclosed herein is preferably 45 inclusive of all of the characteristics above generally set forth, but with some of the characteristics of different construction and arrangement. The structure of my present invention is inclusive of a socket 50 holder, a lamp receiving socket within

said holder and smaller in cross section than the bore of the holder, an incandescent lamp having its base within the aforesaid socket, this lamp base being smaller in cross section than the bore of the socket, means pressing the socket laterally against one side of the aforesaid holder to position the socket with respect to the holder, and additional means pressing the lamp base against one side of the socket to position the lamp filament with respect to both socket and holder. The means that presses the socket against the holder is preferably a spring or springs integrally formed with the holder. The means that presses the lamp base against the socket is 60 also preferably a spring or springs, integrally formed with the socket.

If the holder be associated with a reflector, the position of the lamp filament with respect to the reflector is assured, it being understood that the lamp filaments of the incandescent lamps which are to be used in the structures of my invention preferably occupy predetermined uniform positions with respect to the lamp bases. To further assure 70 the precise positions of the lamps, I desirably provide V-shaped seats in the bayonet slots that receive the bayonet pins upon the lamps, so that the lamps are brought to a uniform position rotatively. The lamp 75 socket, in the structure of my invention, is preferably prevented from having any longitudinal adjustment, so that the spacing of the lamp filament from the reflector is fixedly determined. This construction obviates the 80 necessity of a special design for the reflector which has hitherto been proposed to procure the same lighting effect with the filament in different positions along the reflector axis. The invention, however, is not to be thus 85 limited.

The invention will be more fully explained in connection with the accompanying drawings showing the preferred embodiment thereof, and in which Fig. 1 is a plan view 90 with a portion of the reflector shown in section; Fig. 2 is a view from beneath, part of the bulb being broken away; Fig. 3 is a side view; Fig. 4 is a sectional view on line 4-4 of Fig. 1; Fig. 5 is a sectional view on line 100

5—5 of Fig. 4; Fig. 6 is a sectional view on line 6—6 of Fig. 4; Fig. 7 is a perspective view illustrating component parts of the structure in separated relation; and Fig. 8 6 is a sectional elevation taken through the axis of the parabolic reflector.

The lamp illustrated includes a housing or back element 1 having a bracket 2 on its bottom side by which it may be assembled 10 with the automotive vehicle or other support, as indicated. The housing or back 1 encloses a parabolic reflector 3 which is formed with a grooved flange 4 at its forward end. This flange is pressed against a rim 5, provided upon the housing, by an assembling 15 ring 6. This assembling ring also presses the light transmitting closure 7, usually of glass, against a gasket 8 which is seated in the flange 4.

20 The generally cylindrical socket holder 9 has its forward end passed through a circular opening formed through the crown of the reflector, in the embodiment of the invention shown. The forward end of the 25 holder 9 is formed with flanges 10 and 11 between, which the surrounding edge portion of the reflector is clamped, whereby the holder and reflector are maintained coaxial, in the structure illustrated.

30 The generally cylindrical lamp socket 12 is held in assembly with and within the holder 9 by the means hereinafter set forth. This socket is preferably formed with a single bayonet slot or channel 13 for receiving 35 a bayonet pin or projection 14 upon the base 15 of an incandescent lamp. This bayonet pin is maintained in a V-shaped retaining seat 13' of the bayonet slot by any suitable means, the V-shaped seat holding the 40 lamp from rotative movement. The means illustrated is inclusive of a coiled spring 16 which surrounds a plunger 17 constituting a circuit terminal and presses forwardly upon the plunger head 18 and rearwardly upon 45 the flange 19 of a metallic guiding sleeve 20. This guiding sleeve is mounted upon an insulating disc 21 which is fixedly assembled with and within the rear end of the socket 12. The plunger head 18 presses against a contact 22 which is carried by the generally cylindrical lamp base 15 which is made of 50 insulating material. The lamp structure illustrated is a so-called single pole structure, though the invention is not to be thus limited.

55 Where a single pole structure is employed, the contact 22 is upon the axis of the lamp base. A stiff leading in wire 24 establishes connection between the contact 22 and one terminal of the filament 25. Another stiff leading in wire 26 establishes a connection 60 between the other terminal of the filament and the metallic sheath 27 which surrounds the insulating portion of the lamp base and, from the point of view of my invention, also 65 constitutes a part or enlargement of the lamp

base. The body of the reflector, the holder 9, and the socket 12 are grounded and when the lamp is in place the sheath 27 is also grounded as it has connection with the holder, as will more fully appear.

70 In carrying out my invention the cross section of the socket 12 is smaller than the bore of the holder 9 and the base of the lamp, inclusive of its sheath 27, is smaller, in cross section, than the bore of the socket.

75 Spaced apart spacing means intervene between the holder 9 and the socket 12. These spacing means are preferably in the form of ribs 28 which extend along the holder and socket. Each rib is desirably integrally formed with one of the elements 9 or 12, both ribs being shown as being integrally formed with the holder. The ribs are spaced less than 180 degrees apart, preferably 120 degrees apart.

80 The means for pressing the socket 12 against the holder 9 is desirably inclusive of four spring tongues 29 which are integrally formed with the holder 9. These springs are arranged in spaced apart pairs, the springs of each pair being also 85 spaced apart. The socket 12 is formed with lugs 30 pressed outwardly therefrom. Each lug is snugly received between two longitudinally related springs 29, whereby the

90 socket is prevented from having longitudinal movement, so that the filament of the lamp is fixed longitudinally of the axis of the reflector. By this preferred construction, it is unnecessary to specially design the reflector as would be desirable if the lamp socket 95 were movable along the lamp axis. The springs 29 engage the adjacent side of the socket and press the opposite side of the socket evenly against the ribs 28, the line of

100 pressure being between these ribs. In this way, the axis of the socket is fixed with respect to the reflector. The side 13' of the bayonet slot 13 in the socket 12 also constitutes a spring tongue which presses inwardly against the adjacent side of the lamp base. This spring exerts pressure on a line 105 between the ribs 31 that are shown as being formed upon the lamp base and lengthwise thereof. These ribs engage the socket and accurately define the position of the lamp 110 lengthwise of the structure. As the V-shaped bayonet seat 13' prevents rotative movement of the lamp, the filament of the lamp is accurately positioned with respect to the reflector, this position being predetermined if the filaments of all lamps to be used in my device are accurately positioned with respect to the lamp bases.

115 Changes may be made without departing 120 from the invention.

Having thus described my invention, I claim:

130 1. The combination with a socket holder; of a lamp receiving socket within said holder and smaller in cross section than the bore of

- the holder; an incandescent lamp having its base within said socket, said lamp base being smaller in cross section than the bore of the socket; a bayonet pin on said lamp base; a 5 V-shaped bayonet seat in said socket for said pin: means pressing said pin against said seat; spacing ribs extending longitudinally of the holder and socket and intervening between said holder and said socket; spacing 10 ribs extending longitudinally of the socket and lamp base and intervening between said socket and said lamp base, the ribs intervening between the holder and the socket being in register with the ribs intervening between 15 the socket and the lamp base; a pair of spring tongues on said holder adapted to press against said socket; a formation on said socket adapted to be engaged between said tongues to prevent longitudinal movement of 20 the socket in the holder; and a spring tongue on said socket adapted to press against said lamp base. 2. The combination with a socket holder; of a lamp receiving socket within said holder and smaller in cross section than the bore of the holder; an incandescent lamp having its base within said socket, said lamp base being smaller in cross section than the bore of the socket; spacing ribs extending longitudinally 25 of the holder and socket and intervening between said holder and said socket; spacing ribs extending longitudinally of the socket and lamp base and intervening between said socket and said lamp base, the ribs intervening 30 between the holder and the socket being in register with the ribs intervening between the socket and the lamp base; a pair of spring tongues on said holder adapted to press against said socket; a formation on said socket adapted to be engaged between said 35 tongues to prevent longitudinal movement of the socket in the holder; and a spring tongue on said socket adapted to press against said lamp base. 40 3. The combination with a socket holder; of a lamp receiving socket within said holder and smaller in cross section than the bore of the socket; an incandescent lamp having its base within the aforesaid socket, said lamp 45 base being smaller in cross section than the bore of the socket; spring means integral with the holder pressing the socket laterally against one side of the aforesaid holder to position the socket with respect to the holder; spring means integral with the socket pressing the lamp base against one side of the socket to position the lamp filament with respect to both socket and holder; spacing ribs 50 extending longitudinally of the holder and socket and intervening between these elements in the place at which the socket is pressed against the holder; and spacing ribs extending longitudinally of the socket and 55 lamp base and intervening between these ele- 60 65
- ments in the place at which the lamp base is pressed against the socket.
- In witness whereof, I hereunto subscribe my name.
